[57] CLAIM

The ornamental design for a bean cutting frame, substantially as shown and described.

DESCRIPTION

FIG. 1 is a front perspective view of a bean cutting frame showing the top and left side of my new design, both long sides being symmetrical;

FIG. 2 is a bottom, rear, right side perspective view thereof; and

FIG. 3 is a front, top, right side perspective view thereof.

FIG. 1

FIG. 2

FIG. 3
